Richard F. Landwehr, Laurelton, N. Y., and Simon Morrison, New Brunswick, N. J., assignors to Sagamore Metal Goods Corporation, New York, N. Y., a corporation of New York

Application December 24, 1940, Serial No. 97,598

Term of patent 7 years

To all whom it may concern:

Be it known that we, Richard F. Landwehr, a citizen of the United States and a resident of Laurelton, in the county of Queens, State of New York, and Simon Morrison, a citizen of the United States and a resident of New Brunswick, in the county of Middlesex, State of New Jersey, have invented a new, original, and ornamental Design for a Combined Salt Shaker, Pepper Shaker, and Stand Therefor, of which the following is a specification, reference being had to the accompanying drawing, forming part thereof.

We claim:

The ornamental design for a combined salt shaker, pepper shaker, and stand therefor, substantially as shown.

RICHARD F. LANDWEHR.
SIMON MORRISON.
